US0D1082648S

(12) **United States Design Patent** (10) Patent No.: **US D1,082,648 S**
(45) Date of Patent: ** Jul. 8, 2025

(54) **FOLDING WINGED IN HOVER, CARGO VTOL AIRCRAFT**

(71) Applicant: **GADFIN LTD.**, Rehovot (IL)

(72) Inventor: **Eyal Regev**, Mazkeret-Batya (IL)

(73) Assignee: **GADFIN LTD.**, Rehovot (IL)

(**) Term: **15 Years**

(21) Appl. No.: **29/898,224**

(22) Filed: **Jul. 25, 2023**

(30) **Foreign Application Priority Data**

Jan. 31, 2023 (IL) 70166

(51) LOC (15) Cl. **12-06**

(52) U.S. Cl.

USPC **D12/16.1**

(57) **CLAIM**

The ornamental design for a folding winged in hover, cargo VTOL aircraft, as shown and described.

DESCRIPTION

FIG. 1 is a front, top, right-side perspective view of the folding winged in hover, cargo VTOL aircraft in an open condition;

FIG. 2 is a back, bottom, left-side perspective view thereof;

FIG. 3 is a top view thereof;

FIG. 4 is a bottom view thereof;

FIG. 5 is a right-side view thereof;

FIG. 6 is a left-side view thereof;

FIG. 7 is a front view thereof;

FIG. 8 is a back view thereof;

FIG. 9 is a front, top, right-side perspective view of the folding winged in hover, cargo VTOL aircraft in a closed condition;

FIG. 10 is a back, bottom, left-side perspective view thereof;

FIG. 11 is a top view thereof;

FIG. 12 is a bottom view thereof;

FIG. 13 is a right-side view thereof;

FIG. 14 is a left-side view thereof;

FIG. 15 is a front view thereof; and,

FIG. 16 is a back view thereof.
